US0D1060684S

(12) **United States Design Patent** (10) Patent No.: **US D1,060,684 S**
(45) Date of Patent: ** Feb. 4, 2025

(54) **PROBE FOR AN ULTRASONIC DIAGNOSIS DEVICE**

(71) Applicant: **CANON MEDICAL SYSTEMS CORPORATION**, Otawara (JP)

(72) Inventors: **Satoshi Shinata**, Kanagawa (JP);
Hiroyuki Shikata, Tochigi (JP)

(73) Assignee: **Canon Medical Systems Corporation**,
Otawara (JP)

(**) Term: **15 Years**

(21) Appl. No.: **29/912,104**

(22) Filed: **Sep. 13, 2023**

(30) **Foreign Application Priority Data**

May 23, 2023 (JP) ..... 2023-010387 D

(57) **CLAIM**

The ornamental design for a probe for an ultrasonic diagnosis device, as shown and described.

DESCRIPTION

FIG. 1 is a perspective view of a probe for an ultrasonic diagnosis, showing my new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a left-side elevational view thereof; and,
FIG. 7 is a right-side elevational view thereof.

1 Claim, 7 Drawing Sheets
